THERMAL INSULATING MATERIAL AND
METHOD OF MAKING THE SAMEThomas D. Cole, Lockport, N. Y., assignor to
Lockport Cotton Batting Co., Lockport, N. Y.

Application May 7, 1949, Serial No. 91,912

8 Claims. (Cl. 154—28)

1

This invention relates to thermal insulating material of the type commonly used for building insulation or for insulating other structures and which is made of fibrous materials.

One of the objects of this invention is to provide insulating material in the form of batts, panels or the like, requiring less fibrous material without diminishing the bulk or volume thereof. Another object is to provide an improved process for making material of this type.

A further object is to provide insulating batts, panels or the like, of this type made of a plurality of layers of loosely matted fibrous material and in portions of which the layers are less densely packed than in other portions.

Other objects and advantages will be apparent from the following description of one embodiment of the invention and the novel features will be particularly pointed out hereinafter in connection with the appended claims.

In the accompanying drawings:

Fig. 1 is a perspective view of a thermal insulating batt or panel embodying this invention.

Fig. 2 is an end view of a panel of larger size which may be cut to form batts or smaller panels of the desired size.

Cotton insulation batts or panels have heretofore been made by placing thin layers of flame-proofed or otherwise treated cotton as they are discharged from garnetting machines one on another until the desired thickness of the insulating panel has been built up.

In accordance with this invention, the thermal insulating panels or batts are made of relatively thin films or webs of matted, fibrous material superimposed one upon the other, and some portions of the films or webs of the sheet material are laid in folded or overlapping relation in contact with each other while other portions of the films or webs are arranged in spaced or loosely packed relation to each other, thus forming relatively larger air cells between these last mentioned portions of the film or web.

In my improved insulating material, the panels or pieces of insulating material are divided into alternate zones arranged substantially parallel to each other crosswise of the direction of feed of the films or webs of the fibrous material. In one series of zones the web insulating material is folded back on itself and in the other zones, the film or web is fed straight across such zones without folding. As a result, the portions of the films or webs in the first mentioned zones will lie in contact with each other in the same manner as in prior insulating panels. In the other zones, arranged between the first mentioned zones,

2

there are fewer layers of web of material, so that in the intermediate zones the layers are not compressed and tend to expand or fluff up so that they appear of increased thickness, as shown in the drawings. These layers may be spaced from each other or contact only lightly with adjacent layers. Consequently, in these intermediate zones the layers tend to form larger or more air spaces between the fibers and between the layers.

10 In the manufacture of insulating material of this type of a single or continuous film or web of matted fibrous material as it is discharged from a machine, such for example as a garnetting machine, in accordance with my invention, this film or web is folded upon itself or overlapped, as shown by way of example in Fig. 2. In this figure, a film or web of fibrous material may start at 5 and then be folded back on itself and then forwardly, thus producing three layers within the 15 first zone 6 of the insulating panel. This material in Fig. 2 is shown as lying on a table, conveyor belt, or other support 27.

The sheet of material then passes directly and without folding to a second zone 7 where it is 20 similarly folded back upon itself, and then passes on to successive zones 8 and 9, in which the sheet material is folded in a similar manner until it passes to the last zone 10, at which the film or web may be given a number of folds and is then passed back to zones 9 and 8 and 7 respectively, at which zones the web of material 25 may be folded back on itself in the same manner as already described in connection with those zones. At zone 6, in which the web of material must be turned back to repeat the fold in the 30 other zones, a plurality of folds may be made in the material. The number of folds made in zones 6 and 10 may vary, it being desirable to arrange the folds in these zones in such a manner that when the panel has been completed, each of the 35 zones 6, 7, 8, 9 and 10 will have substantially the same number of layers of material therein.

In the other or intermediate zones 11, 12, 13 and 14, it will be noted that materially fewer layers of the fibrous material are provided, and 40 these layers 15 because of the nature of this fibrous material or batting, tend to expand so that they appear thicker than the layers in zones 6 to 10. These layers in the other zones may be spaced from each other or contact lightly with 45 each other so as to form relatively larger air cells in and between the layers. After the material has been folded over in the zones 6, 7, 8, 9 and 10, to produce the desired thickness of the batt, the film or web of material is passed straight across 50 the various zones without folding, thus forming a

finishing surface 17 for the outer faces of the panel.

The structure described results in the forming in each of the zones 6 to 10 a column extending throughout the length of the batt or panel. These columns determine the thickness of the panel and also enable the built up panel or batt to retain its required shape. The columns also form supports for the layers or films of the fibrous material extending across the spaces between these columns in such manner that larger air spaces or pockets are formed in zones 11 to 14 due to the density of the material being less in these zones. Since the fibrous material is of a fluffy nature, the material forms larger air spaces between the fibers in these zones than in the zones 6 to 10, in which the material is more compacted. The columns in zones 6 to 10, consequently, support the layers which are stretched across the other or intermediate zones and hold these layers more or less in suspension. By having the uppermost layer 17 extending straight across the panel or batt without folding, the columns in the zones 6 to 10 are connected to hold the same in correct relation to each other and to form additional air spaces.

I have illustrated by way of example only five zones in which the material is folded or overlapped on itself, but it will, of course, be understood that panels of material of materially greater widths may be made by continuing the folding of the web of material in a number of additional zones. Similarly smaller panels with fewer zones and of less widths may be made.

When the folding is completed, the material may be cut lengthwise along the lines 18 to form batts or panels of the required dimensions, the cuts being made in zones in which the material is folded. The resulting panels or batts, such for example as shown in Fig. 1, will then have the fibrous insulating material in the two end zones at the sides of the batt and in an intermediate zone laid face to face and in the other zones or spaces between the first mentioned zones the layers will be arranged in substantially spaced relation to each other, thus forming relatively larger air spaces and less density of material. The batt described is of lighter weight per unit of volume than batts heretofore made of similar material, since it contains less material. Since the material is of a loose felted nature, it is not necessary to secure the layers of the film or web to each other by adhesive or other external means, since the fibers of one layer of material will felt together with the fibers of an adjacent layer in contact therewith, so that it is merely necessary to lay one layer of material against an adjacent layer to secure the necessary adhesion between the sheets or layers, but sewing or other securing means may be employed, if desired.

The batts or panels when cut to the desired dimensions may be used in any suitable or usual manner. For example, the batts may be secured to paper sheets 19 in the usual manner, as shown in Fig. 1, the edges of the sheets extending beyond the batts to permit them to be nailed or otherwise secured to the studs or rafters and, if desired, the opposite faces and edge portions of the batts may, of course, be covered with other paper sheets, as has heretofore been common practice.

Fibrous materials of animal, mineral or vegetable origin or synthetic fibers may be employed for producing insulating material according to this invention.

It will be understood that various changes in the details, materials, and arrangements of parts which have been herein described and illustrated in order to explain the nature of the invention, may be made by those skilled in the art within the principle and scope of the invention, as expressed in the appended claims.

I claim as my invention:

1. A thermal insulating panel comprising a plurality of relatively thin layers of a film of readily compressible fibrous material superimposed one upon another, said panel having a plurality of zones extending parallel to each other in which the layers are folded back and forth within said zone, and other zones located intermediate said first mentioned zones and across which said layers extend without folding, said plurality of layers in said first mentioned zones forming columns extending throughout the length of said panel which determine the thickness of said panel and which support the unfolded layers in said other zones in partly suspended relation to each other, said material in said first mentioned zones being compressed to a greater extent than the material in said other zones and the film in said other zones being expanded into greater thickness than the film in said first zones to form a panel of substantially the same thickness throughout.

2. A thermal insulating panel according to claim 1 in which the uppermost layer of said fibrous material extends straight across the panel without folds to bridge the spaces between said columns.

3. A thermal insulating panel formed of a continuous thin film of readily compressible fibrous material arranged in a plurality of layers, said panel comprising a plurality of zones extending parallel to and spaced from each other, each successive layer of said film being overlapped upon itself within said zones and extending across the spaces between zones without overlapping, the material in said zones supporting the weight of the material in said spaces between said zones and being compacted thereby, said material in said spaces being free to expand to substantially fill said spaces and to form larger air spaces between the fibers, said overlapped portions of said film in said zones forming columns extending lengthwise of said panel and forming supports for the unfolded layers in the spaces between said columns.

4. A method of making a thermal insulating panel, comprising laying a film of matted readily compressible fibrous insulating material in a series of layers extending successively in opposite directions crosswise of the panel, said panel having a plurality of zones extending parallel to and spaced from each other and from the edges of said panel, and folding said film of material upon itself in overlapping relation within said zones, and passing the film from one zone to the next without overlapping in the spaces between said zones, to produce more layers of material in said zones than in the spaces between said zones.

5. A method of making a thermal insulating panel, comprising laying a film of readily compressible fibrous insulating material in a series of layers extending successively in opposite directions crosswise of the panel, folding said film back on itself within certain zones in said panel at the edges of the panel and intermediate of the edges thereof to form a plurality of overlapping layers in said zones, and passing the material without folding across the spaces between zones.

6. A method of making a thermal insulating

panel of a series of layers of a film of readily compressible fibrous material, comprising laying said film in a zone at one edge of the panel first toward the opposite edge thereof, then back toward the first edge and then forward to the opposite edge, then laying said film without folding across a space from said zone toward another zone, repeating the folding in said other zone and in successive spaced zones, then laying said film in the opposite direction from said opposite edge toward said first edge and repeating the folding of the film in said zones, and continuing the laying and folding in said zones until the panel at said zones has attained the required thickness, to form larger air spaces in the films in said spaces between zones.

7. A method according to claim 6 and including the laying of the last layer of the panel across from one edge to the opposite edge without folding the same in said zones.

8. A thermal insulating panel comprising a plurality of layers of garnetted cotton superimposed

one upon another, said panel having a plurality of zones extending substantially parallel to each other which contain more of said cotton than the spaces between said zones, the cotton which extends across the spaces between said zones being supported by the cotton in said zones, said cotton in said zones being compressed and the cotton extending across said spaces being free to expand and forming larger air spaces between the fibers, said panel being of substantially uniform thickness throughout.
